HIGH VOLTAGE TERMINAL CONSTRUCTION
AND METHOD OF ASSEMBLY

Franklin S. Smith, New Haven, Conn.

Application December 14, 1931, Serial No. 580,910

19 Claims. (Cl. 173—318)

This invention relates to high voltage terminal construction and method of assembly thereof.

One of the objects of this invention is to provide a thoroughly practical, simple and inexpensive terminal construction well adapted to function at high voltages and to provide a method of relating such a terminal to the tank, container or casing that houses the high voltage apparatus in a manner that is simple, thoroughly practical, and well adapted to meet the peculiar requirements of practical use. Another object is to provide a terminal construction of the above mentioned nature adapted to withstand relatively high differences of pressures between the outside and inside thereof and to achieve a construction in which danger of leakage of dielectric is dependably precluded. Another object is to provide a high voltage terminal construction adapted to function in coaction with a tank or container containing the high voltage apparatus immersed in a gaseous dielectric under high pressure and to provide a method and apparatus for reliably and dependably achieving a sealed joint or connection between the terminal construction and the container, all without detrimentally affecting the electric or other characteristics or qualities of the apparatus contained within the tank or container. Another object is to provide a construction of the above mentioned character in which assembly and disassembly thereof may be reliably and dependably achieved while making certain that in assembly sealed joints or connections are quickly and dependably achieved. Other objects will be in part obvious or in part

35 pointed out hereinafter.

The invention accordingly consists in the features of construction, combinations of elements, arrangements of parts and in the several steps and relation and order of each of the same to one or more of the others all as will be illustratively described herein, and the scope of the application of which will be indicated in the following claims.

In the accompanying drawing in which is shown a preferred embodiment of my invention,

Fig. 1 is a vertical central sectional view of a high voltage terminal construction related to its tank or container, and

Fig. 2 is an enlarged vertical central sectional view of the upper part of the terminal construction virtually as seen in Fig. 1.

Similar reference characters refer to similar parts throughout the several views of the drawing.

55 Referring now to the drawing and more par-

ticularly to Fig. 1, I have shown a container 10 preferably of cylindrical form and preferably made of pressed steel so as to insure its withstanding substantial differences of pressure between the interior and exterior thereof. When made of pressed steel the container 10 may and preferably does have its bottom 10a formed integrally therewith. The container is adapted to be closed by an end shell or closure member 11 also preferably made of pressed steel and shaped so as to be received within the upper open end of the container or tank 10; the closure member 11 is curved adjacent its peripheral portions so that the upper peripheral portions 10b of the container 10 may thereafter be bent over onto the closure or shell 11 and the parts then welded together as at 12, thus insuring a mechanically small construction and one that is hermetically sealed.

Within the container 10 is mounted and supported in any suitable manner the high voltage apparatus which may take any form, and solely by way of illustration I have indicated in the drawing a transformer as comprising the apparatus within the sealed container. This transformer I have indicated purely diagrammatically and it may comprise a low voltage winding 13, connection to which may be made from the exterior through any suitable terminal construction sealed into a suitable portion of the walls of the enclosing container; this terminal construction may take the form, for example, shown in my copending application Serial No. 511,309, filed January 26, 1931, now Patent No. 1,907,599.

The transformer has a high tension winding 14 one or both of the terminal connections of which may be brought out through the high voltage terminal construction which includes certain features of my invention and which will be described in detail hereinafter. Illustratively, however, I have shown one end of the high voltage winding 14 as being grounded to the tank 10—11 in any suitable way and at any suitable point; diagrammatically this one terminal is grounded by conductor 15 to the container 10 so that it will suffice to describe in detail how the other terminal of the high voltage winding 14 is brought out through the casing and insulated therefrom.

I first provide an opening of suitable size in a suitable portion of the closure and illustratively I have shown that opening as of circular shape and positioned centrally and hence coaxially of the closure member 11. Into this opening is snugly fitted, from the interior thereof (before the assembly of the closure 11 to the tank 10), a col-

lar 16 provided with a laterally and peripherally projecting flange 16a adapted to overlap the under or inner face of the closure 11, the latter being bezelled, if desired, to receive the flange 16a.

5 The joint between the collar 16 and the container wall is further strengthened mechanically and is also sealed by welding these parts together as at 17.

10 Collar 16 is interiorly stepped or turned down to provide a shoulder 16b and a second shoulder 16c, and drilled into the shoulder 16b and aligned about a circle is a plurality of holes 16d that extend parallel to the axis of the collar 16; these holes 16d are tapped so that they may later receive suitable securing screws.

15 The upper portion of the collar 16, as viewed in Fig. 1, is bored out and is threaded; this thread may be of any suitable construction and it may, if desired, be somewhat tapered, approximating 20 in that respect a pipe thread.

Collar 16, as will be pointed out in detail hereinafter, is to support, at its threaded portion, the high voltage terminal construction.

25 But interfitting with the interior shoulder or stepped portions of the collar 16 is an annular member 18, preferably of metal, and provided with an annular rib or lip 18a adapted to rest against the shoulder 16c of the collar 16 and adapted to snugly fit into and to be centered by 30 the cylindrical wall adjacent the shoulder 16c.

35 Projecting to the right of the rib 18a is a flange-like portion 18b which overlaps the shoulder 16b, and passing through the flange 18b are suitable screws 19 that are received in the threaded holes 16d of the collar 16, thus to hold the annular member 18 in place.

40 The latter has an inwardly and upwardly directed lip 18c which, as appears clearly from Fig. 1, extends upwardly into substantial parallelism with the annular rib or lip 18a but extends upwardly beyond the latter so as to be positioned 45 interiorly of but parallel to the upper and inner threaded portion of the collar 16, all for a purpose to be more clearly described hereinafter. The upper end of the inner lip 18c is tapered as at 18d.

45 The electrical apparatus within the tank 10—11 is immersed in a gaseous dielectric under relatively high pressure, for example, in a gas like nitrogen under a pressure on the order of 15 atmospheres. The coaction of this gaseous dielectric under pressure with various parts of the high voltage apparatus, illustratively the transformer 13—14, need not here be dealt with but it may be pointed out that the maintenance of the difference 50 of pressure between the inside and the outside of the casing or container must be maintained not only to insure the intended functioning of the high voltage electrical apparatus but also of the preferred form of high voltage terminal construction that I prefer to employ.

55 This terminal construction includes a tube-like housing 20 of solid dielectric material, such as phenolic condensation product, and it is made of substantial thickness not only to achieve certain coactions in insulating the high voltage conductor but also to withstand the difference of pressure between the interior and exterior thereof. Preferably the housing 20 is somewhat tapered, being conveniently and illustratively proportioned somewhat as is shown in Fig. 1.

70 At its upper end the housing 20 is internally threaded as at 20a, these threads being preferably molded into the member 20 when the latter is formed, and threaded into the upper end of member 20 is a plug 21 (see also Fig. 2), the lower end

80 of which is bored out but tapered as at 21a to snugly receive and hold a tapered plug 27 to which is secured a tubular conductor 22, the latter being secured in place in a manner described more clearly hereinafter, and being thus held coaxially with the member 20; as appears from Fig. 1, the member 22 extends downwardly to a substantial extent where it coacts with a metal bushing 23 with respect to which it is likewise held coaxially.

85 The sleeve-like insulating member 20 is interiorly threaded at its lower end as at 20b, these threads being also preferably formed during the process of molding the member 20, and it is with the threads 20b that the upper outer threaded portion of the metal sleeve-like bushing 23 coacts. The threaded connections between the upper plug 21 and the housing 20 and between the latter and the bushing 23 are not only of sufficient mechanical strength to withstand the difference 90 of pressure between the inside of the construction and the outside thereof but also are airtight, being sealed if desired with any suitable cement or sealing composition. These joints, because of their character, it is undesirable to disturb or disconnect once the airtight joint or joints has or 95 have been made.

100 The inner cylindrical wall or face 23a of bushing 23 will be seen to be spaced from the high tension conductor 22 and, moreover, the radii of curvature of this inner face and of the tubular conductor or lead 22 are such that the ratio therebetween is equal to or less than 2.718, forming thus a fast discharge gap filled with the gaseous dielectric under high pressure, which gap will 105 break down instantaneously at a certain voltage and, moreover, will break down without the breakdown being preceded by corona. The critical breakdown voltage of this fast discharge gap is such that the gap breaks down when a voltage 110 greater than that which the electrical apparatus within the container can safely withstand is imposed upon the high voltage circuit or lead 22.

115 Preferably the upper and lower interior ends 120 23b and 23c of the bushing 23 are rounded at 125 preferably a relatively large radius of curvature to prevent undesirable flux concentration at these points and thus to prevent interference with the functioning of the fast discharge gap above described.

125 The high voltage end of the high voltage winding 14 of the transformer is in electrical connection with the lead 22, the high voltage terminal construction thus far described achieving 130 a coaction with the gaseous dielectric under pressure and with the solid dielectric material of the housing 20 such that the high voltage circuit may be safely led into or out of the sealed casing 10—11.

135 The lower end of bushing 23 is threaded as at 23d to mate with the threaded part of the collar 16, and it is also provided with an axially directed annular recess 23e into which the flange or lip 18c of the member 18 is received as the bushing 23 is threaded down into the collar 16. The bushing 140 23 is provided with a laterally directed flange 23f preferably provided with peripheral openings 24 and 25 adapted to receive the prongs or studs of a spanner wrench so that the bushing 23 with the terminal construction carried thereby may be 145 threaded into the collar 16 and a substantial rotating force or energy exerted thereon.

150 In assembling the terminal construction with respect to the casing 10—11 and the electrical apparatus therein contained, either initially or after

disassembly had subsequently taken place, a suitable conductor 26 is led from the terminal end of the high voltage apparatus (high voltage winding 14, for example) and threaded upwardly 5 through the tubelike conductor 22, whence (see particularly Fig. 2) it is passed through the hollow tapered plug 27, thence outwardly through the bore of the plug 21.

The threaded portion 23d of the bushing 23 10 and the threaded part of collar 16 are coated or "tinned" with a layer, of suitable thickness, of a suitable sealing alloy which, by way of example, may be an alloy known as "amaloy" which consists of about 98% of lead, approximately 2% of tin, and the remainder, a small fraction of 1%, 15 of phosphorus.

The terminal construction, with the conductor 26 threaded completely therethrough, is now ready to be assembled to the collar 16 and hence 20 to the casing 10-11. The threaded portions of the bushing 23 and collar 16 are interengaged, the spanner wrench applied to the projecting flange 23f by engaging it with the openings 24-25, and the rotation of the bushing 23 with its supported 25 construction commenced.

As the rotation proceeds, the tight interfitting of the threaded parts or of the threads, made tighter by the coated alloy on one or both of these threaded parts, produces such a resistance to 30 turning that a substantial quantity of heat is generated at the threads and the alloy virtually fuses or melts, the rotation of the bushing 23 proceeding until the bushing is sufficiently driven home, whereupon the cooling off of the parts results virtually in a hermetic sealing of the parts together. 35

During the threading of the bushing 23 into the collar 16 and the resultant fusing or melting of the alloy, it is possible that some of the fused 40 alloy is sufficiently released to cause it to drop away from the joint being formed. If any such particles of this alloy are allowed to enter the casing 10-11, the electrical properties of the apparatus contained therein might be very detrimentally affected; for example, short circuits 45 might be caused or, if there is included in the container a dielectric material such, for example, as ground fused quartz or ground Pyrex glass, as is disclosed in my copending application Serial No. 580,908, filed December 14, 1931, these particles 50 of the alloy would intermingle therewith and badly affect if not entirely destroy its insulating properties throughout at least certain portions thereof.

But as the bushing 23 is threaded downwardly, 55 as viewed in Fig. 1, any such particles of the alloy that might drop from the joint being formed are caught in the annular space between the lips 18a and 18c of the member 18. Furthermore, these particles are permanently entrapped so that even 60 though the apparatus were to be inverted from the position shown in Fig. 1, such particles could not escape. This latter action is achieved not only by virtue of the tight fit of the lip or flange 18a with the interior of the collar 16 but also 65 by the interfitting and interlocking of the inner and upwardly elongated lip or flange 18c with the lower part of the bushing 23, into the annular recess 23e of which this lip enters and tightly 70 interfits, this entry being facilitated by the tapered peripheral portion 18d of the lip 18c. Thus 75 I am enabled to achieve a dependable seal between these metallic parts and to prevent the sealing operation and/or materials used therein from interfering with the ultimate action of the apparatus sealed within the container.

Having driven the bushing 23 with the parts carried thereby home, the conductor 26 may now be anchored at its upper end (see Fig. 2) and the hollow plug 21 sealed. This may be achieved by the following construction:—

The metal tube or conductor 22 is secured to the lower end of the hollow tapered plug 27 in any suitable manner; the latter is interiorly threaded to receive a hollow screw 29 whose head 29a abuts against an inside shoulder 21b of the plug member 21; it is by the screw 29 that the tapered plug 27 is drawn up into the tapered bore 21a of the plug 21 and thus securely held in place, and it is also through the hollow screw 29 that the conductor 26 is initially threaded. 80

The upper end of the plug 21 is closed by hollow plug 33 which may be secured in place in any way, as by threading, and through this plug also the conductor 26 is threaded. The conductor 26, after the assembly of the terminal construction as above described, is now drawn sufficiently taut, is cut off substantially flush with the upper end of the plug 21 and its short end is then bent over in any suitable way onto the upper surface of the plug 33. 85

Then there is inserted a suitable sealing means such as a plug 35 of lead, which is inserted on top of the bent over end of the conductor 26 and this lead plug may then be hammered out or expanded laterally in any suitable way. Thereupon a 105 plug 34 is threaded into the remaining portion of the reduced upper end bore of the plug 21 and is driven home, additionally tightly compressing the lead plug 35 and thus hermetically sealing the bore of the plug 21 against the escape of the 110 gaseous dielectric under pressure within the casing 10-11 and within the terminal construction. If desired, the joint between plug 34 and part 21 may be soldered. 100

The upper outer end of the plug 21, which projects beyond the upper end of the housing 20, may 115 be threaded to receive any desired means, such as a nut or the like, with which to electrically connect the exterior circuit in coaction with which the high voltage apparatus or device within the 120 casing 10-11 is to function.

The gaseous dielectric under pressure may be 125 injected into the casing and hence also into the interior of the terminal construction by any suitable means (not shown).

Should it become necessary to disassemble the 130 construction, the gaseous dielectric under pressure may first be released in any suitable way or it may be released through the hollow plug 21. First the screw plug 34 is removed, then the lead sealing plug 35, whereupon the conductor 26 is 135 sufficiently released so that the entire terminal construction may be rotated, to disconnect the threaded bushing 23 from the collar 16, without rotating and twisting the conductor 26. During this unscrewing action, the device 18 again acts 140 to prevent any of the sealing alloy that might be melted or otherwise dropped from the threaded portions as a result of the unthreading of the parts from falling into the casing 10-11.

As above pointed out, the parts 22 and 23 form 145 a fast discharge gap. The member 18 (Fig. 1) is preferably of metal but its effective diameter or radius, with respect to the radius of the rigid conductor 22, is sufficiently greater than the radius of the cylindrical surface 23a of the bushing 23 to prevent spark-over, through the gaseous dielectric under pressure, between the part 18 and the part 22. Moreover, the member 18 is, throughout the portions exposed toward high voltage 150

parts, given a curvature of relatively great radius so as to avoid concentration of flux and so as further to reduce the possibility of undesired spark-over thereto from high voltage parts 5 of the apparatus.

Depending upon various facts, the hermetic sealing of the threaded joint between the parts 16 and 23 may be carried on, as desired, either by 10 solder the parts together, or simply by the cold flow of the alloy; in the former case sufficient heat is made effective at the joint to cause melting of the alloy while in the latter case the achievement of such heat at the joint may be dispensed 15 with. Where it is undesired or impracticable to provide the necessary heat, the cold relatively soft metal, illustratively the above-mentioned alloy, is made to flow cold under the confinement thereof by the threads of the parts and the pressure or 20 forces exerted thereon. In either of the above-mentioned cases, the device 18 and particularly the coaction therebetween and the bushing 23 achieve a dependable and effective mechanical seal as against the entry into the sealed container 25 10—11 of particles of the sealing metal that would otherwise drop into the casing; moreover, these features of construction and coaction also prevent the entry into the casing of particles or parts of the threaded members 16 and 23 that 30 might be dislodged therefrom or sheared off in the course of the interthreading of these parts. Moreover, it will be seen that this mechanical seal has a dependable and wide range of action 35 throughout and in spite of the relative movement that takes place between the collar 16 and the bushing 23 as the latter is threaded into the former.

While I have above specifically mentioned a preferred form of sealing alloy, I wish it to be 40 understood that any other suitable alloy or suitable metal may be employed in its stead and I do not wish to be limited to the specific alloy illustratively above disclosed, nor do I wish to be limited to a sealing metal or alloy having the 45 specific melting point of the alloy above mentioned.

It will thus be seen that there has been provided in this invention a construction and method of assembly in which the various objects hereinbefore noted together with many thoroughly practical advantages are successfully achieved.

As many possible embodiments may be made of the mechanical features of the above invention and as the art herein described might be 50 varied in various parts, all without departing from the scope of the invention, it is to be understood that all matter hereinabove set forth or shown in the accompanying drawing is to be interpreted as illustrative and not in a limiting 55 sense.

I claim:—

1. In high voltage terminal construction, in comb'nation, a member having a threaded opening through which a conductor is to be passed, a terminal construction having a bushing threaded 60 at one end for coaction with said member and having sealed thereto a solid dielectric housing having a conductor sealed through its remote end, one of said threaded parts having a soft metal applied to the threads thereof, and means in sealed connection with said first mentioned member and having a part adapted to engage said bushing as the latter is threaded into said opening for entrapping metal particles disengaged from the parts being interthreaded.

2. In high voltage terminal construction, in combination, a member having a threaded opening through which a conductor is to be passed, a terminal construction having a bushing threaded 65 at one end for coaction with said member and having sealed thereto a solid dielectric housing having a conductor sealed through its remote end, said threaded parts being proportioned tightly to interfit, and means carried by said first mentioned member and projecting inwardly about the region of the threaded part thereof for catching metal particles disengaged from the parts being interthreaded. 80

3. In terminal construction, in combination, a casing having therein an electrical apparatus and having a threaded opening, means projecting from the wall of said casing into said opening, an insulating terminal construction having a threaded bushing adapted to be threaded into said opening, said bushing having an annular recess into 90 which said projecting means fits as the bushing is threaded into the opening. 95

4. In terminal construction, in combination, a casing having a threaded opening and annular means of less diameter than the diameter of the 100 threaded opening, said annular means projecting in alignment with the axis of said opening, and an insulating terminal construction including a threaded bushing adapted to be threaded into said threaded opening, said bushing having an 105 annular recess into which said annular means is received upon said bushing being threaded into said opening.

5. In terminal construction, in combination, a casing adapted to receive an electrical apparatus 110 and having an opening therein, a threaded collar secured in said opening, an insulating terminal construction including a threaded collar and insulating means associated therewith, said collars being adapted to be interthreaded, and an annular flange projecting from one of said collars, the other of said collars having an annular recess into 115 which said flange is received to form a sealed enclosed space about those threaded portions of said collars that are otherwise exposed toward the 120 interior of said casing.

6. In terminal construction, in combination, a casing adapted to receive an electrical apparatus and having an opening therein, a threaded collar secured in said opening, an insulating terminal 125 construction including a threaded collar and insulating means associated therewith, said collars being adapted to be interthreaded, a part projecting from one of said collars and into the path of movement of the other, and means on the 130 other collar adapted to interfit with said projecting means to form an enclosure about the threaded portions of the collars that are otherwise exposed toward the interior of said casing.

7. In terminal construction, in combination, a 135 casing adapted to receive an electrical apparatus and having a threaded opening therein, metallic means in sealed connection with said casing and extending about said opening and providing a flange of lesser diameter than said opening and 140 extending parallel to the walls of the latter, a terminal construction comprising a threaded bushing adapted to be threaded into said opening and carrying insulating means which supports a conductor concentrically with said bushing, the 145 radii of curvature of said conductor and of said bushing being proportioned so as to form a fast discharge gap, said bushing being shaped to form a substantially sealed connection with said flange as the bushing is threaded into said opening. 150

- said metallic means having a radius of curvature sufficiently great to prevent interference thereby with the action of said fast discharge gap.
8. In terminal construction, in combination, a casing adapted to receive an electrical apparatus and having a threaded opening therein, metallic means in sealed connection with said casing and extending about said opening and providing a flange of lesser diameter than said opening and 5 extending parallel to the walls of the latter, a terminal construction comprising a threaded bushing adapted to be threaded into said opening and carrying insulating means which supports a conductor concentrically with said bushing, the radii of curvature of said conductor and of said bushing being proportioned so as to form a fast discharge gap, said bushing being shaped at its lower end to telescope with said flange as said bushing is threaded into said opening, the effective 10 radius of curvature of said metallic means being greater than said radius of curvature of said bushing.
9. In terminal construction, in combination, a casing adapted to receive an electrical apparatus and having a threaded opening therein, metallic means in sealed connection with said casing and extending about said opening and providing a flange of lesser diameter than said opening and 15 extending parallel to the walls of the latter, a terminal construction comprising a threaded bushing adapted to be threaded into said opening and carrying insulating means which supports a conductor concentrically with said bushing, the radii of curvature of said conductor and of said bushing being proportioned so as to form a fast discharge gap, said bushing having an annular recess adjacent its lower portion within which 20 said flange is received as said bushing is threaded into said opening.
10. In terminal construction, in combination, a casing adapted to receive an electrical apparatus and having an opening therein whose wall is threaded, an insulating terminal construction including a metal member having an external 25 threaded wall and insulating means associated therewith, one of said threaded walls having applied thereto prior to assembly of the parts a metallic sealing alloy, and means for preventing alloy dislodged by the interthreading of said parts from dropping into said casing.
11. In terminal construction, in combination, a casing adapted to receive an electrical apparatus and having an opening therein whose wall is threaded, an insulating terminal construction including a metal member having an external 30 threaded wall and insulating means associated therewith, one of said threaded walls having applied thereto prior to assembly of the parts a metallic sealing alloy, and means completely 35 enveloping those portions of the threaded joint that are exposed interiorly of said casing for entrapping alloy particles disengaged from the parts being interthreaded.
12. In terminal construction, in combination, a casing adapted to receive an electrical apparatus and having an opening therein whose wall is threaded, an insulating terminal construction 40 including a metal member having an external threaded wall and insulating means associated therewith, one of said threaded walls having applied thereto prior to assembly of the parts a metallic sealing alloy, and means associated with 45 those portions of the threaded joint that are exposed interiorly of said casing for entrapping alloy particles disengaged from the parts being interthreaded.
13. In terminal construction, in combination, a casing adapted to receive an electrical apparatus and having an opening therein whose wall is threaded, an insulating terminal construction including a metal member having an external threaded wall and insulating means associated therewith, one of said threaded walls having applied thereto prior to assembly of the parts a metallic sealing alloy, and means in sealed connection with the inside wall of said casing and forming a joint with said metal member as the latter is threaded into said opening for entrapping alloy particles disengaged from the parts being interthreaded.
14. The method of sealing a terminal construction having a threaded metal part onto a casing having a threaded part which consists in applying to at least one of said threaded parts an alloy of low melting point, and utilizing the heat generated during the interthreading of said threaded parts to cause the alloy to flow.
15. The method of sealing a terminal construction having a threaded metal part onto a casing having a threaded part which consists in first applying a sealing metal to the threads of one of said parts, interthreading said parts, and entrapping particles of the sealing metal dislodged by the interthreading of said parts.
16. The method of sealing a terminal construction having a threaded metal part onto a casing having a threaded part which consists in applying a metallic sealing means to one of said threaded parts and interthreading the latter while maintaining a mechanical seal of the joint exposed interiorly of said casing against the dropping into the casing of dislodged particles of the metallic sealing means.
17. In terminal construction, in combination, a casing having a threaded part, a terminal construction having a threaded part, and means maintaining a mechanical seal against the passage of solid particles about those portions of the threaded parts that are exposed to the interior of said casing.
18. In terminal construction, in combination, a casing having a threaded part, a terminal construction having a threaded part, and means forming an extensible seal against the passage of foreign particles from those portions of the threaded parts exposed to the interior of said casing.
19. In terminal construction, in combination, a casing having a threaded part, a terminal construction having a threaded part, and means forming a mechanical seal between those portions of the threaded parts exposed to the interior of said casing, said seal being constructed to function throughout relative movement between said threaded parts.

FRANKLIN S. SMITH.
